UNITED STATES PATENT OFFICE.

WILLIAM H. HIDLEBAUGH, OF GOULD, OKLAHOMA.

AIR-HOSE COUPLING FOR RAILWAY-CARS.

1,170,534.

Specification of Letters Patent.

Patented Feb. 8, 1916.

Application filed September 8, 1914. Serial No. 860,665.

To all whom it may concern:

Be it known that I, WILLIAM H. HIDLEBAUGH, a citizen of the United States, residing at Gould, in the county of Harmon, 5 State of Oklahoma, have invented certain new and useful Improvements in Air-Hose Couplings for Railway-Cars; and I do hereby declare the following to be a full, clear, and exact description of the invention, such 10 as will enable others skilled in the art to which it appertains to make and use the same.

This invention relates to air hose couplings for railway cars.

15 The object of the invention resides in the provision of a device of the character named which will serve to automatically unite the adjacent ends of train pipe sections of an air brake system when the cars carrying 20 such adjacent ends of the train pipe are themselves coupled.

A further object of the invention resides in the provision of a train pipe coupling in which the adjacent ends of the train pipe 25 are normally closed by a valve associated with each section of the pipe, and which embodies means whereby said valves are automatically opened by engagement of the coupling heads with each other.

30 With the above and other objects in view the invention consists in the details of construction and in the arrangement and combination of parts to be hereinafter more fully described and particularly pointed out 35 in the appended claim.

In describing the invention in detail reference will be had to the accompanying drawings wherein like characters of reference denote corresponding parts in the several views, and in which—

Figure 1 is a plan view of the coupling just previous to the movement of the parts thereof into coupling relation; Fig. 2, a view similar to Fig. 1 partly in section and 45 with the parts in coupling relation; Fig. 3, a side view of what is shown in Fig. 2; Fig. 4, a section on the line 4—4 of Fig. 2; Fig. 5, a perspective view of a fragment of one of the coupling heads, and Fig. 6, a perspective view of the valve mounted in the head for closing the passage therein, said 50 valve being shown removed.

Referring to the drawings the coupler is shown as comprising a pair of coöperating heads A and B which are pivotally connected at their inner ends within tubular draw

bars A' and B' respectively. These draw bars A' and B' are each offset at their outer ends as at 10 so that by reversing the draw bars with respect to their tops and bottom 60 they may be employed on different heights of cars effectively. Each of the draw bars A' and B' is connected to the car for limited longitudinal movement and is normally held at the limit of said movement in one 65 direction by springs 11. Projecting from the outer end of each draw bar A' and B' are leaf springs 12 which engage the sides of the associated head and resist any tendency of such head to swing laterally on its 70 pivotal connection with its draw bar. By this construction, the outer ends of the heads A and B are held in firm contact when the associated cars are rounding a curve. Each of the heads A and B comprises a 75 body 10' the outer end of which terminates in major and minor V-shaped fingers 11' and 12' respectively, a resultant V-shaped recess 13 being thereby formed between the fingers 11' and 12'.

80 Each of the heads A and B is provided with a longitudinal passage 13' in the inner end of which is engaged a pipe 14 which is connected to the adjacent end of a train pipe 15. The outer end of the passage 13' 85 opens through the side of the finger 11' adjacent the finger 12'. The flow of air through the passage 13' is controlled by a valve 16 mounted in the associated head. The valve 16 of each head A has secured 90 thereto an operating handle 17 having a cam edge 18. A spring 19 has one end secured to the handle 17 and its other end anchored to the associated head, said spring 95 constantly tending to move the valve 16 to closed position. Movement of the valve 16 under the influence of the spring 19 is limited by a stop 20 secured to the associated head and preventing movement of the valve beyond closed position. Rotatably mounted 100 upon the finger 11' of each head at the point of said finger is a roller 21 which is adapted to engage the cam edge 18 of the handle 17 of the valve mounted on the other head during the coupling operation for the 105 purpose of opening the valve 16 automatically.

Upon movement of the coupling heads from the position shown in Fig. 1 to the position shown in Fig. 2 it will be obvious 110 that the fingers 11' will enter the recesses 13. During this movement of the heads A and

B the rollers 21 of one head will engage the cam face 18 of the handle 17 on the other head and operate respective valves 16 to open position.

5 Secured on the bottom of the head A is a spring 24 the outer end of which is curved outwardly as at 25 and serves to assist the heads A and B to move together into interlocking relation. The passage 13' 10 is also controlled by an emergency valve 26 having a handle 27 adapted to engage over the pivotal connection between each head and the associated draw bar to lock said valve 26 in open position.

15 It will be noted that the couplers herein described can be provided with a plurality of air passages and all of said passages controlled by the operation of a single valve.

What is claimed is:—

20 In an air hose coupling, the combination of a pair of yieldingly supported coöperating heads, said heads having their adjacent ends provided with outwardly tapering fingers adapted to move into interlocking rela-

tion when the heads are moved toward each other, an air pipe line mounted in each head and provided at one end with means for connection to a train pipe and having their other ends positioned to be disposed in registration when the heads are interlocked, a 30 valve in each of said pipe lines, a handle on each valve having a cam edge, spring means secured to each handle and constantly tending to move the associated valve to closed position and the handle in bridging 35 relation with respect to the space between the fingers of the related head, and a roller journaled on the outer end of one of the fingers of each head and adapted to engage the cam edge of the handle on the other head 40 during the coupling movement of said heads to operate the valves to open position.

In testimony whereof, I affix my signature, in the presence of two witnesses.

WILLIAM H. HIDLEBAUGH.
